UNITED STATES PATENT OFFICE.

HEDLEY WATTY, OF GROTON, CONNECTICUT.

CHIMNEY-HOLDER.

1,242,748.

Specification of Letters Patent.

Patented Oct. 9, 1917.

Application filed June 24, 1916. Serial No. 105,743.

To all whom it may concern:

Be it known that I, HEDLEY WATTY, a citizen of the United States, residing at Groton, in the county of New London and 5 State of Connecticut, have invented certain new and useful Improvements in Chimney-Holders, of which the following is a specification.

This invention relates broadly to illuminating burners, and more particularly to an 10 improvement in devices whereby the chimney of the usual liquid fuel burning lamp may be securely held thereupon.

It is the principal object of the invention, 15 to provide a device of the character stated, whereby, the chimney of the lamp will be engaged by suitable means for preventing accidental dislodgment thereof, under all conditions.

20 Among the aims and objects of the invention may be recited, the provision of a chimney holding device in which the number of parts are few, the construction simple, the cost of production small, and efficiency and 25 operation high.

The invention may be stated briefly, to comprehend, a plurality of hooks which are connected with the chimney by means of eyelets arranged thereon, these hooks being 30 engageable with the burner. Springs are arranged upon the hooks in order that the same may be extended and also, to afford a yieldable connection.

Other and further improvements and 35 novel details in the construction and arrangement of parts will be appreciated from the description to follow, which for a clear understanding of the invention, to be considered in connection with the accompanying 40 drawings, which form a part hereof, and wherein the preferred embodiment of the invention is disclosed for the purpose of illustration.

In the drawings:—

45 Figure 1 is a side elevation of a lamp with my improved attachment applied thereto, and

Fig. 2 is a detail in perspective of the securing hooks.

50 With more particular reference to the drawings, wherein like reference numerals refer to corresponding parts throughout the several views, it may be stated, that I have indicated the usual liquid fuel burning lamp 55 by the numeral 1, including with this, the usual burner, while the chimney is desig-

nated by the numeral 2. It is of course understood, that the burner is provided with a plurality of engaging arms whereby the lower portion of the chimney 2 is retained 60 in proper position, upon the burner of the lamp, this being the usual construction and therefore forms no part of the present invention. In the preferred embodiment of my invention, I form upon the chimney 2, 65 at points adjacent the base thereof, a plurality of eyelets which are generally indicated by the numeral 3. It is to be understood, that these eyelets may be blown with the lamp chimney during the making 70 thereof, or if so desired, may be attached thereto in any manner as known to the art. With these eyelets 3, I engage arms 4, looping the same as at 5, in order that the same may be maintained in connection therewith. 75 In describing the construction of these arms in detail, attention is directed to the fact, that each arm is constructed in exact accordance and therefore mention will be made of but one in the detailed description to follow. The hooks 4 comprise a strip of bendable metal, the lower end of which is bent inwardly to constitute a hooked portion 6, while contractile springs of the coiled type, designated as 7, are formed with the arms 4, 80 substantially intermediate the ends thereof. Finger loops 8 are formed upon the lower extremities of the arms and provide for means whereby the various hooks may be 85 readily disengaged from the underface of the lamp burner when it is desired to remove the chimney 2 from the lamp. The finger pieces 8 fully well serve as means whereby the hooks may be engaged with the underface of said lamp burner, in applying the 90 chimney to the lamp.

From the foregoing, it will be understood, that when the user desires to place the chimney 2 upon a lamp burner, the same is first engaged with the resilient engaging arms as 100 arranged upon the burner in the usual manner. The finger pieces 8 as arranged upon the arms 4 and then engaged whereupon the hook portions 6 as formed upon the lower extremities of said arms may be readily 105 moved into engagement with the underside of the lamp burner. When the hooks have been engaged with the lamp burner in the manner as above described, it is obvious that accidental displacement of the shade, due to 110 shifting of the lamp will be positively prevented, also, that the contractile coiled

springs 7 as formed in the arms 4 will serve as means for applying a constant pull upon the said chimney, thus, retaining the same upon its seat. It will be readily understood that should the user desire to remove the shade chimney, the action will be vice-versa.

While I have herein disclosed a specific embodiment of the invention, it will be apparent to persons skilled in the art, that the invention is capable of embodiment in other forms and devices differing in detail and arrangement from that shown as may be in keeping with the hereto appended claims.

Having thus described the invention, what is claimed is:—

1. A device of the character described, including, in combination with a lamp chimney having a plurality of eyelets arranged thereon, of arms connected with said eyelets and having springs formed integral therewith intermediate the end portions thereof, and hooks formed upon the lower extremities of said arms engageable with

the buruer of a lamp and adapted to yieldably secure the chimney to these arms.

2. A device of the character described, including, in combination with a lamp having a plurality of eyelets arranged thereon adjacent the base portion, of arms formed from bendable material connected with said eyelets, said arms having coiled springs formed therein intermediate the ends thereof, hooks formed upon the remaining ends of the arms engageable with the burner of a lamp whereby the chimney may be yieldably held thereon, and finger loops arranged upon said arms to facilitate the engagement and disengagement of the arms to and from the burner.

In testimony whereof I affix my signature in presence of two witnesses.

HEDLEY WATTY.
